UNITED STATES PATENT OFFICE.

PHILIP B. ROHNER, OF CARROLL, IOWA, ASSIGNOR OF ONE-HALF TO ANDREW A. DREES, OF CARROLL, IOWA.

AIR-BRAKE-RELEASE VALVE.

Application filed October 23, 1925. Serial No. 64,332.

To all whom it may concern:

Be it known that I, PHILIP B. ROHNER, of Carroll, in the county of Carroll and State of Iowa, a citizen of the United States, have 5 invented certain new and useful Improvements in Air-Brake-Release Valves, of which the following is a specification.

This invention relates to air-brake release valves of the type disclosed in Letters-Patent No. 1,452,495, issued April 24, 1923, the 10 object of the present invention being to provide a construction which will reduce flow through the diaphragm when the brake is to be released so that the air will be caused 15 to escape through the lowest or auxiliary port. The invention is illustrated in the accompanying drawing and will be hereinafter fully set forth and defined.

In the drawings—

20 Figure 1 is a sectional elevation of a release valve with the parts in normal position;

Figure 2 is a top plan view of the diaphragm as it appears in Figure 1; and

25 Figure 3 is a bottom plan view of the diaphragm as it appears when releasing the brakes.

The main valve body comprises an upper member 1, a lower member 2, and a coupling 30 sleeve 3 threaded into the opposed meeting ends of the two members whereby to secure them rigidly together. The bore of the upper body member 1 is so shaped as to provide a valve chamber 4 therein and the main 35 outlet port 5 leads from the bore and communicates with said chamber through the bore which is preferably lined with a bushing 6, the lower end of the bushing extending into the chamber 4 and providing a seat 40 for the main valve 7. A stem 8 rises from the valve to bear against a rocker 9 mounted on top of the valve body whereby the valve may be moved to open position. A stem 10 depends from the valve through the coupling 45 and fits loosely in the intermediate port 11 provided at the center of the coupling by the bore thereof, the bore of the coupling being enlarged, as at 12, above the port to provide a support for the spring 13 which 50 acts with the air pressure to hold the valve 7 normally seated. The lower end of the coupling is flared, as at 14, to provide a chamber which will direct air escaping from the brake cylinder or auxiliary reservoir 15 to the port 11. Slight grooves 16 are formed

in the marginal portion of the lower end of the coupling for a purpose which will presently appear. The lower body member 2 is cupped or dished in the bottom of the chamber 17 in which the lower end of the coupling 60 is secured, and through wall of said cupped bottom are formed one or more auxiliary ports 18. A nipple 19 depends from the body member 2 and is threaded into the cylinder 15, as shown. The auxiliary ports 65 18 are normally closed by a diaphragm 20 of rubber or like material which is shaped to normally form an inverted cone, seating snugly on the bottom of the chamber in the upper end of the body member 2 and extending over and closing the ports 18. In the apex of the diaphragm, a narrow slit 21 is formed therethrough. Under normal conditions, the slit 21 is open, as shown in Figure 2, and air from the cylinder 15 70 flows therethrough to and through the intermediate port 11 and acts upon the valve 7 to hold it seated.

To release the brakes, the rocker 9 is actuated to depress and unseat the valve 7 80 80 whereupon the air will rush to and through the main outlet port. The increased pressure thus exerted upon the diaphragm lifts it from its seat and drives it against the lower end of the coupling to cover and close the intermediate point, folding or inverting 85 of the diaphragm resulting. During this action any air which may be trapped between the diaphragm and the coupling will escape through the grooves 16 and around 90 the edge of the diaphragm to pass out through the auxiliary ports 18. Instantly upon the diaphragm being lifted, the rocker 95 may be released permitting the valve 7 to seat whereupon the air pressure will hold the diaphragm raised until, by escaping through the auxiliary ports 18, it is reduced to the desired degree whereupon the diaphragm will return to normal position. When the diaphragm is lifted and reversed 100 upon itself as described, the walls of the slit 21 are pressed together so that flow through the diaphragm is cut off and the diaphragm will be held to the port 11 to close the same. Should air be trapped above 105 the diaphragm, vibration of the diaphragm will result and this will produce a pumping action driving the air around the edge of the diaphragm to the ports 18. The grooves 110 16 facilitate this circulation,

Having thus fully described my invention, what I claim as new and desire to secure by Letters Patent of the United States, is—

- 5 1. In a brake release device, a diaphragm having normally an inverted conical form with its apex presented to the flow of pressure fluid, there being a narrow slit through the apex of the diaphragm held open under
10 normal pressure but closing under increased pressure which tends to flatten and invert the diaphragm.
- 15 2. In a brake release device, the combination of upper and lower body members, a coupling connecting said members, and provided with grooves in the marginal portion of its lower end, and an outlet port in the upper body member, a manually operable valve controlling flow to said outlet port,
20 an auxiliary outlet port in the lower body member, an inlet portion in the lower body member, and a diaphragm seating on the lower body member and normally closing the auxiliary outlet, said diaphragm having
25 a narrow slit therethrough normally open

to permit passage of pressure fluid but closing under increased pressure tending to seat the diaphragm against the coupling whereby to cut off flow to main outlet port and direct flow to the auxiliary outlet port. 30

3. In a brake release device, the combination of upper and lower body members, a coupling connecting said members, an outlet port in the upper body member, a manually operable valve controlling flow to said outlet port, an auxiliary outlet port in the lower body member, an inlet portion in the lower body member, and a diaphragm seating on the lower body member and normally closing the auxiliary outlet, said diaphragm 35 having a narrow slit therethrough normally open to permit passage of pressure fluid but closing under increased pressure tending to seat the diaphragm against the coupling whereby to cut off flow to main outlet port and direct flow to the auxiliary outlet port. 40

45 In testimony whereof I hereunto affix my signature.

PHILIP B. ROHNER.
